UNITED STATES PATENT OFFICE

2,683,475

MINE TIMBERING MACHINE HAVING A
TIMBER CUTTING UNIT

George W. Miller, Chicago, Ill., assignor to Goodman Manufacturing Company, Chicago, Ill., a corporation of Illinois

Application June 16, 1951, Serial No. 232,025

10 Claims. (Cl. 143—32)

1

This invention relates to improvements in vehicles for installing timbers in mines, and more particularly to improvements in machines for sawing mine timbers to size at the time of installation in a mine.

One of the principal objects of the invention is to provide a vehicle having a timber cutting unit readily adjustable to cut a timber while it is disposed either longitudinally along one side of the vehicle, or transversely along one end of the vehicle, as dictated by operating conditions and requirements.

A further object is to provide a vehicle having a flat deck for transporting a plurality of timbers into proximity to the place where they are to be installed in the mine, and with the clamping and cutting unit movable into position to receive a timber by gravity from said deck, and to facilitate the handling of said timber.

A still further object of the invention is to provide trough means along the side of the vehicle, adapted to be moved into an out-of-the-way position relative to the vehicle when the side trough means is not being used in cutting a timber.

Another object is to provide an adjustable interconnecting means between the cutting unit and the trough means at one side of the vehicle, so that the trough means will be automatically swung into its out-of-the-way position when the cutting unit is swung so as to cut a timber disposed transversely at one end of the vehicle.

A further object is to provide a combined clamp and safety guard element operable in conjunction with the sawing mechanism, having means for engaging the timber with minimum danger of catching the operator's fingers therebetween.

Other objects and advantages of the invention will appear as the following description proceeds.

The invention may best be understood by reference to the accompanying drawings, in which:

Figure 1 is a plan view of a mine vehicle constructed in accordance with my invention;

Figure 2 is a side view of the vehicle;

Figure 3 is an enlarged detail view of the clamping and cutting unit, taken on line 3—3 of Figure 1;

Figure 4 is a detail section taken on line 4—4 of Figure 3;

Figure 5 is a fragmentary perspective view of the clamping and cutting unit, with parts broken away and shown in section to show certain structural details;

2

Figure 6 is a fragmentary perspective view showing the operating interconnection between the clamping and cutting unit and the folding trough supports along one side of the vehicle;

Figure 7 is a detail plan view of one of the folding trough supports.

Referring now to details of the embodiment of my invention shown in the drawings, a self-propelled mine vehicle 10 has mobile traction means, herein consisting of track wheels 11 which may be driven as usual by power of a motor suitably mounted on the vehicle. The power drive for the traction means need not be shown in detail as it forms no part of the present invention.

The vehicle 10 includes a main frame 12 surmounted by a generally flat deck 13 for carrying a plurality of mine timbers either lengthwise or transversely thereof. A plurality of removable pins 14, 14 may be provided along the sides of the deck for retaining timbers thereon during transportation of the latter.

A housing 15 of relatively limited horizontal dimensions projects above said deck near the front end of the vehicle, containing mechanism for actuating and controlling the movement of a boom 17, which is provided with a saddle 18 at its outer end for elevating or holding a mine beam in position for installation in the mine. The general arrangement and function of such a boom is well known in the art so need not be further described.

The vehicle has a platform 19 projecting from the front end thereof below the deck level, which platform is recessed at one corner of the frame as indicated at 20, to receive a clamping and cutting unit 21. Said unit is pivotally mounted for horizontal swinging movement on an upright pin 22, which herein is supported at its lower end in the base of platform 19 and at its upper end in a bracket 23 projecting forwardly from the vehicle frame along the outer side of the recess 20. The clamping and cutting unit 21 is of generally elongated box-shape, and is arranged to be swung substantially into the recess 20 in one position, for cutting timbers supported transversely of the front end of the vehicle, and to be swung outwardly of the recess with its major portion extending laterally of the adjacent side wall 24 of the vehicle frame, in a second position for cutting timbers supported along said side wall of the vehicle frame. In the form shown, an upstanding bracket 25 is fixed near the end of platform 19 opposite the clamping and cutting unit 21 with a V-shaped

upper face to receive one end of a timber. A pair of brackets 26 and 27 are hinged to the side wall 24 in spaced relation to each other, in the form shown the rearmost bracket 26 being disposed substantially at the rear corner of the vehicle, and the other bracket 27 being substantially halfway toward the rear of the vehicle. Further details of the hinged brackets 26 and 27 will be hereinafter described.

Referring now to details of the clamping and cutting unit 21 shown in Figures 3, 4 and 5, said unit includes a hollow box-like housing consisting of a bottom wall 28, side walls 29, 30 and end walls 31, 32, all rigidly secured to each other as by welding. Said housing also has an intermediate upright partition 33 parallel with the side walls 29 and 30. A cover plate 34 extends horizontally from partition 33 to the adjacent end wall 30 and may be detachably secured to said walls as by bolts 35. A second narrower cover plate 36 spans the opposite side of the housing along the end wall 29 but is spaced from the first-named cover plate 34 so as to form an elongated slot 37 extending longitudinally of the top of said housing. The cover plates 34 and 36 both have aligned V-shaped trough supports 34a and 36a, respectively, extending to the opposite sides of the housing for the reception of a timber or log during the sawing operation.

An elongated sawing element 40 and a clamping element 41 are pivotally mounted within the housing with their swinging ends projecting through the slot 37 and movable by power toward and away from each other transversely of the trough line defined by the troughs 34a and 36a.

In the form shown herein, the sawing element 40 consists essentially of an endless saw chain 42 of the straddle type, guided orbitally about an elongated guide plate 43. Said guide plate is adjustable endwise on a block 44 having an offset hub 45 rotatably mounted on a hollow bearing support 46. The chain may be driven as usual by a sprocket 47 loosely mounted on shaft 48 extending through the bearing support 46, and the sprocket being driven through a conventional slip friction clutch, indicated at 49. The parts of the elongated sawing element enumerated above are well known in the art, so further details need not be shown nor described, excepting as to the novel means for mounting and operating said element in conjunction with the associated parts of the machine.

The shaft bearing support 46 extends through a reduced aperture in a cup-shaped supporting ring 51 fixed as by welding in the upright partition 23. Said bearing support has a flange 52 at its inner end, detachably secured as by bolts 54 in a central recess 55 of ring 51, opening to the outer side of said ring. The ring 51 also has a flanged periphery 56 for housing a flywheel 57 keyed on the end of drive shaft 48 for the chain sprocket 47. The flywheel 57 preferably has an effective inertia value of at least four times that of the saw chain.

A cover plate 59 is secured by bolts 60 to the flanged periphery 56 of cup-shaped ring 51 and has a hydraulic motor 61 mounted thereon, with its rotor shaft (not shown) having driving connection, as usual, with the adjacent end of the chain drive shaft 48.

The sawing element 40 is swung by power of a double-acting hydraulic cylinder 65, having one end pivoted as at 66 to the side wall 31, and with its piston rod 67 pivoted at 68 to an arm 69 projecting from the hub 45 of the sawing element.

It will be noted that the axis of swinging move-

ment of the sawing element is disposed near the juncture of the bottom wall 28 and the inner end wall 32 of unit 21. Said sawing element is thus normally retracted to a generally horizontally inoperative position within the unit, below the V-shaped trough members 34a and 36a thereof, and is swung upwardly and outwardly relative to the inner end wall 31 and the vehicle 10, during the sawing of a timber.

The clamping element 41 consists of an elongated claw-like guard arm 70 of considerable width, with an inwardly curved outer end 71 having toothed flanges 72, 72a along opposite sides thereof, in laterally spaced relation to each other, to provide gripping edges for a timber, in spaced relation on opposite sides of the path of swinging movement of the sawing element. In the form shown, the teeth 73 on flanges 72 are of substantially greater length than the thickness of the average human hand, so as to aid the operator in removing his fingers from danger should they be accidentally caught between the clamping member and a timber during the operation of the machine.

The clamping arm 70 is pivotally mounted within the box-like housing on an axis adjacent the juncture of the bottom wall 28 and the inner end wall 31, in the form shown herein the pivotal axis of said clamping arm being coaxial with that of the sawing element 40. The pivotal support for said clamping arm includes a cheek plate 74 fixed along the inner end of one of the side flanges 72 of said arm, and pivotally mounted on a stub shaft 75 carried by a bearing stud 76 detachably mounted on the adjacent wall 29. Preferably, the bearing stud 76 extends through the side wall 29, and has a flanged outer end portion 77 detachably secured by bolts 78 in a recess 79 formed in the outer face of said wall, so that the bearing stud 76 and shaft 75 can be removed from the outer side of the unit for facilitating assembly or disassembly of the parts.

The cheek plate 74 is extended beyond its pivotal mounting to form a lever arm 80 pivotally connected at its outer end at 81 to a piston rod of a double-acting hydraulic cylinder 82. The opposite end of said cylinder is pivoted at 83 to side wall 31. Fluid pressure is supplied to opposite ends of the cylinder 82 through suitable hydraulic control devices (not shown) for swinging the clamping arm bodily on its axis. In the form shown, a second cheek plate 84 is detachably secured as by bolts 85 to the other side flange 72a of clamping arm 70, and the last-named cheek plate is pivotally supported on the exterior of the hollow bearing support 46, in which the chain drive shaft 48 is journalled, concentrically with the axis of the bearing stud 76 on which the opposite cheek plate 74 is journalled.

The clamping arm 70 and its actuating cylinder 82 are arranged so that said clamping arm, when in open non-clamping position, is disposed in a generally upright position, with its outer end extending out of the slot 37 on top of the cutting unit 21, adjacent the side wall 32.

The clamping arm is swung inwardly and downwardly to hold a timber in the adjacent trough supports 34a and 36a, in a direction opposite to the swinging movement of the sawing element 40 when cutting the timber held in place in the trough by the clamping arm.

By reason of the horizontal pivotal mounting of the cutting and clamping unit 21 as a whole relative to the frame of the vehicle as previously described, said unit can be adjusted in one posi-

tion shown in full lines in Figure 1, for cutting a timber disposed longitudinally of the vehicle at one side thereof, or can be adjusted to a second position indicated in dotted lines in Figure 1, for cutting a timber disposed transversely of the vehicle at the front thereof.

The folding supporting brackets 26 and 27 pivotally mounted to the side of the vehicle frame are interconnected with the cutting and clamping unit so that they can be automatically extended by power into proper supporting position when said unit is adjusted in the longitudinal or side-cutting position, and retracted or folded in out-of-the-way position when said unit is adjusted in the transverse or end-cutting position. The interconnecting means is shown in detail in Figures 6 and 7. The brackets 26 and 27 each have upper and lower arms 90 and 91, respectively, pivoted on upright pins 92, 92 on the side of the vehicle frame. The upper arms 90 have levers 93 extending at an intermediate angle therefrom, and pivotally connected to a push rod 94 extending longitudinally along the inner side of the vehicle frame. The front end of said push rod is pivoted intermediate the ends of a lever 95 by pin 96. The lever 95 has one end pivoted to a lug 97 mounted on the vehicle frame, and its other end pivoted to one end of a link 98. The other end of said link is pivoted to the lug 99 fixed to the inner end wall 31 of the clamping and cutting unit 21; that is to say, the end wall nearest the vehicle frame in either cutting position of said unit.

The interconnecting linkage above described is actuated through a double-acting hydraulic cylinder 100 having one end suitably pivoted to the vehicle frame as by lug 101, and has its piston rod 102 pivotally connected to the same pin 96 on the lever 95, which has the push rod 94 pivoted thereon.

The use and operation of the machine above described is as follows:

Timbers of desired length may be transported on the deck of the vehicle, to any place where timbers are to be cut to proper length for installation in the mine. The length of timbers may vary greatly for different purposes and locations, so that it is desirable to cut the timbers to their proper length at the time and place of installation. In most cases, it is preferable to transport timbers much longer than the width of the timbering vehicle, so that the timbers are normally loaded longitudinally of the deck when carried into the mine. The pins 14 aid in keeping the timbers from rolling sideways off the deck but said pins may be removed when desired, to aid in unloading the timbers.

When the area to be timbered is reached, a timber is selected for cutting to the desired length. The clamping and cutting unit is then adjusted by means of the hydraulic cylinder 100 for cutting the timber while held either longitudinally or transversely of the vehicle, depending upon the length desired, and also on the space available for handling relatively long timbers. In many cases, it will be found impossible to swing a timber from a longitudinal to a transverse position for cutting it to length. In such cases, and possibly others, it is more convenient to support the timber on the brackets 26 and 27 along one side of the vehicle frame while cutting it to length. In still other cases, it may be less desirable, or even impossible due to lateral space limitations, to support the timber at the side of the frame, whereupon the timber may be disposed for cutting in transverse position, partially supported on the

fixed bracket 25 on platform 19, and with the other end of the timber engaged in the notched trough supports 34a, 36a of the cutting unit.

In either position of pivoted adjustment of the cutting unit relative to the vehicle, it will be observed that the outer or swinging end of the clamping arm 70, when in open non-clamping position, normally extends generally upright in the slot 37 outside the trough supports 34a, 36a of said cutting unit, to form a stop for timbers when the latter are rolled from the deck 13 and deposited by gravity in cutting position along said trough supports.

Although I have shown and described certain embodiments of my invention, it will be understood that I do not wish to be limited to the exact construction shown and described, but that various changes and modifications may be made without departing from the spirit and scope of the invention as defined in the appended claims.

I claim:

1. A mobile timbering machine comprising a main frame having a timber-supporting deck, a timber-cutting unit mounted on said frame adjacent and below said deck, timber-holding means also mounted adjacent and below said deck in horizontally spaced relation to said unit to cooperate with the latter for supporting a timber in position to be cut, said cutting unit comprising an elongated saw element and a clamping element pivotable about axes located on a side of the timber holding means remote from the frame, and power means for moving said elements toward each other to hold and cut said timber.
2. A mobile timbering machine according to claim 1, in which both of said elements are pivotable about the same axis.
3. A mobile timbering machine according to claim 1, in which the saw element is a cutter bar having a cutter bearing chain orbitally movable thereabout and driving means is provided for the cutter chain comprising a hydraulic motor having a flywheel with an effective inertia at least four times as great as that of the chain.
4. A mobile timbering machine comprising a mobile frame having means for supporting a timber in a position to be cut, a unitary cutting and holding unit thereon comprising a casing having a pair of spaced parallel walls disposed transverse to the axis of the timber when in position to be cut, a support extending inwardly from each of said walls along a common axis, a drive shaft carried by one of said supports rotatable about said axis, a cutter bar mounted on one of said supports for swinging movement about said axis through said timber cutting position and having a cutter chain orbitally movable thereabout, sprocket means carried by said shaft for driving said cutter chain, and clamp means engageable with a timber in position to be cut and comprising separate spaced bifurcations, each of which is pivoted on a respective one of said supports for swinging movement about said axis, one of said supports being mounted for removal from the casing in an outward direction along said axis to facilitate disassembly and assembly of said cutting and holding unit.
5. A mobile timbering machine comprising a mobile frame having a generally flat top deck for transporting a plurality of timbers, a timber cutting and holding unit mounted on said frame comprising notched supporting means at the side of said frame below the level of said deck for supporting a timber deposited therein by gravity from said deck, a clamping element pivoted about

an axis located below said notched supporting means and remote from said frame and swingable by power from a generally upright position beyond said notched supporting means toward the frame for holding a timber in said notched supporting means, and a sawing element movable away from said frame for cutting a timber held in said notched supporting means by said clamping member, said timber cutting and holding unit being wholly disposed beneath the level of said deck excepting for the free end of said clamping element when the latter is in a generally upright position to form a stop for a timber deposited in said notched supporting means from said deck.

6. A mobile timbering machine in accordance with claim 5, in which the mobile frame has timber holding means extending both along one side, and along one end thereof at substantially the same level as the notched supporting means of said cutting and holding unit, and the timber cutting and holding unit is pivotally mounted on the frame at the juncture between the side and end thereof, to be effective for cutting a timber supported in either timber holding means.

7. A mobile timbering machine comprising a main frame having a timber supporting deck, timber holding means extending along one side and one end of said deck below the level thereof in position to receive a timber thereon by gravity from said deck, and a timber cutting and holding unit pivotally mounted on the frame below said deck at the juncture between the side and end timber holding means, said cutting and holding unit being pivotally adjustable to cut a timber supported in either of said timber holding means.

8. A mobile timbering machine in accordance with claim 7, in which the timber cutting and holding unit is mounted for horizontal swinging movement through a range of ninety degrees to

selectively cut and hold timber in either the end or side positions along said frame.

9. A mobile timbering machine in accordance with claim 7, in which the side timber holding means includes at least one bracket pivotally mounted on the side of the frame, and linkage means is pivotally mounted on the frame interconnecting the bracket and the cutting and holding unit to move said bracket into extended supporting position in alignment with the cutting and holding unit when the latter is positioned for cutting the timber along the side of the frame.

10. A mobile timbering machine in accordance with claim 9, in which the side timber supporting bracket is pivotal between a timber holding position normal to the frame side in an out-of-the-way position lying substantially flush against said side, and the linkage means interconnects the cutting and holding unit and the bracket for concurrent pivotal movement so that the bracket is moved into its out-of-the-way position when the cutting and holding unit is swung into alignment with the timber holding means at the end of the frame.
